UNITED STATES PATENT OFFICE.

EDWIN L. SOUTHWICK AND REUBEN M. SOUTHWICK, OF MALTA, MONTANA.

CUTTER-BAR GUARD.

1,185,442.

Specification of Letters Patent. Patented May 30, 1916.

Application filed August 24, 1915. Serial No. 47,194.

To all whom it may concern:

Be it known that we, EDWIN L. SOUTHWICK and REUBEN M. SOUTHWICK, citizens of the United States, residing at Malta, in the county of Phillips and State of Montana, have invented certain new and useful Improvements in Cutter-Bar Guards; and we do hereby declare the following to be a full, clear, and exact description of the invention, such as will enable others skilled in the art to which it appertains to make and use the same.

This invention relates to guards for cutter bar constructions, such as are used upon mowing machines, harvesters, or like agricultural implements.

The primary object of this invention is to provide a guard finger as specified, which is composed of an upper and lower section, which are pivotally connected, adjacent to the point of the finger or guard, and which have heads formed upon their ends remote from their pivotal ends, for facilitating the connection of the finger guard to a cutter bar, and further to provide means whereby the guard fingers may be attached to any cutter bar of ordinary construction.

With the foregoing and other objects in view this invention consists in such novel features of construction, combination and arrangement of parts as will be hereinafter more fully described, illustrated in the accompanying drawings and claimed.

In describing the invention in detail, reference will be had to the accompanying drawings wherein like characters designate like and corresponding parts throughout the several views, and in which:—

Figure 1 is a plan view of a fragment of a cutter bar, showing a plurality of improved guard fingers attached thereto, Fig. 2 is a side elevation of one of the guards, Fig. 3 is a longitudinal section through one of the guards, Fig. 4 is a cross section through one of the finger guards taken on the line 4—4 of Fig. 2, and Fig. 5 is a perspective view of the ledger plate.

Referring more particularly to the drawings, 1 designates a cutter bar of ordinary construction, to which is attached a plurality of the guards or guard fingers, generally designated by the numeral 2.

The guards 2 include a top section 3 and a bottom section 4, which are pivotally connected as is shown at 5. The bottom section 4 has the ordinary type of point 6

formed thereon, and it is provided with a recess 7 formed in its upper surface and extending downwardly and longitudinally therein. The top section 3 has a tongue 8 formed thereon, which is seated in a portion of the opening 7 and is pivotally connected to the portion of the bottom section 4 which forms the sides of the recess 7, by means of a pin 9.

The top section 3 of the guard, has a boss 10 formed upon its end remote from the end which is pivotally connected at 5, which boss is provided with a slot 11, which is substantially rectangular shaped, and which aligns with a slot 12 formed in the boss 13. The boss 13 is formed upon the ends of the bottom section 4, and is provided for engagement with the under surface of the cutter bar, while the boss 10 engages the upper surface of the cutter bar, for attaching the guards to the cutter bar. The upper surface of the boss 10 is corrugated, as is shown at 14, and it is provided for co-action with the corrugated under surface 15 of the bolt 16. The bolt head 16 is formed upon a bolt 17, which is provided with a rectangular portion 18, that extends through the slot 11 for holding the guard fingers against pivotal movement.

The bottom section 4 of the guard, has an upstanding shoulder 20 formed thereupon, which is provided with a cutout portion 21 formed in the edge of the same which faces the point 6. The cutout portion 21 has its inner wall inclined for snugly fitting the inclined end 22 of the ledger plate 23. The ledger plate 23 has a tongue 24 formed upon the end remote from the beveled or inclined end 22. The tongue 24 is inserted between the sections of the bottom section 4 which forms sides for the cutout portions 7, as is clearly shown in Fig. 3 of the drawings.

To attach the ledger plate 23, the inclined end 22 is inserted within the cutout portion 21 or recess 21, and the ledger plate is moved to a horizontal position, and the tongue 24 within the cutout portion 7, would securely hold the ledger plate attached to the guard. The sides of the ledger plate are serrated, as is shown at 25. The shoulder 20 extends beyond the sides of the body of the guard fingers proper, as is shown at 27, and 28. The projections 27, which extend outwardly from the body of the guard fingers, are provided with hollow conical portions 29, which are adapted for receiving the conical por-

tions 30, which are formed upon the outer ends of the projections 28, for properly spacing and uniting the various guards and also alining a plurality of guard fingers 5 when attached to a cutter bar, as is clearly shown in Fig. 1 of the drawings.

The top section 3 has a plate 31 secured to the under surface of the same, which is adapted to rest upon the upper surface of a 10 sickle bar or cutting knife, for guiding the movement of the same and holding it properly against the upper surface of the ledger plate during its operation.

The boss 13 has a shoulder 33 formed 15 thereon, against which the lower forward corner of the cutter bar 1 engages.

In reducing the invention to practice, certain minor features of construction, combination, and arrangement of parts may necessitate alteration, to which the patentee is 20 entitled, provided such alterations are comprehended within the scope of what is claimed.

What is claimed is:—

25 1. In a cutter bar guard finger structure, a bottom section having a point formed upon one end provided with a cut-out portion extending downwardly therein from its upper surface rearwardly of said pointed 30 end, a top section having a tongue formed therein, said tongue seated in said cut-out portion and pivotally connected to said bottom section, a shoulder formed upon the upper surface of said bottom section and 35 extending transversely across the same, said shoulder being provided with a recess in its side wall facing said point, a ledger plate having one end shaped to conform to and seated in said recess, a tongue formed upon 40 the opposite end of said ledger plate remote from said first-named end, said tongue adapted for insertion into said first-named cut-out portion and for engagement with the under surface of the tongue formed upon 45 said upper section for holding said ledger plate securely in place.

50 2. In a cutter bar guard finger structure, a bottom section having a point formed upon one end provided with a cutout portion 55 extending downwardly therein from its upper surface rearwardly of said pointed end, a top section having a tongue formed thereon, said tongue seated in said cutout portion and pivotally connected to said bottom section, a shoulder formed upon the upper surface of said bottom section and extending transversely across the same, said shoulder being provided with a recess in its side wall facing said point, a ledger

plate having one end shaped to conform 60 to and seated in said recess, a tongue formed upon the opposite end of said ledger plate remote from said first-named end, said tongue adapted for insertion into said first-named cut-out portion and 65 for engagement with the under surface of the tongue formed upon said upper section for holding said ledger plate securely in place, bosses formed upon the ends of said upper and lower sections remote from 70 said pointed end, said bosses being provided with elongated substantially rectangularly shaped slots for receiving bolts for attaching said guard fingers to a cutter bar of ordinary construction. 75

3. In a cutter bar finger guard construction, a bottom section having a cut-out portion formed in one end thereof, an upstanding shoulder formed upon the upper surface of said bottom section and being provided with a recess in its side facing said cut-out portion, a ledger plate, said ledger plate having one end shaped to conform to and seated in said recess, a tongue formed upon said ledger plate remote from said 85 first-named end and adapted for seating in said cut-out portion for holding said ledger plate in snug attachment to said bottom section.

4. In a cutter bar guard finger structure, 90 a finger body, means for adjustably connecting said finger body to a supporting bar, a transversely extending shoulder formed upon said body and having its ends projecting laterally from the sides of the body, one 95 of the projecting ends of said shoulder provided with a substantially conical concaved portion, the other end of said shoulder provided with a substantially conical convex portion formed upon its end for fitting within the concaved portion formed within the projecting end of the shoulder formed upon the finger guard next thereto when a plurality of finger guards are attached to a supporting bar, the insertion of said conical 100 portion into said substantially concaved portion forming means for alining the guard fingers and facilitating their attachment to the supporting bar in proper relation with respect to each other. 105

In testimony whereof we affix our signatures in presence of two witnesses.

EDWIN L. SOUTHWICK,
REUBEN M. SOUTHWICK.
